HAND WEAVING LOOM

Hilma L. G. Berglund, St. Paul, Minn.

Application November 18, 1950, Serial No. 196,495

5 Claims. (Cl. 139—30)

1

This invention relates generally to looms and particularly to a loom constructed to permit the work to be removed in its entirety, and other work to be quickly placed therein.

It has always been a problem in the art of weaving to prepare a loom for the weaving operation. This is a long and tedious job, taking from twelve to twenty-four hours, and requires that each long thread be individually threaded through a number of relatively small openings, and then securely mounted on the cloth roll having previously been attached to the warp roll.

It is an object of my invention to provide a loom structure from which the rolls, the heddle frames, and the reed may be quickly and easily removed to permit the work in its entirety to be replaced with other work in a quick, easy operation.

It is another object to provide a loom in which the heddle frames are placed in individual frame guides and are individually received in pusher cradles which are connected with individual hand levers for selectively raising the individual frames by a pusher action, leaving the top of the loom open and unobstructed to facilitate removal of the frames.

It is a further object to provide a removal and carrying frame structure adapted for easy attachment to the heddle frames, the reed, and the rolls to permit easy removal of all of said elements simultaneously.

These and other objects and advantages of the invention will more fully appear from the following description made in connection with accompanying drawings, wherein like reference characters refer to the same or similar parts throughout the several views, and in which

Fig. 1 is an exploded perspective view of the main loom structure with the removable elements shown thereabove, and the removal and carrying frame structure illustrated at the top; and

Fig. 2 is a transverse vertical sectional view showing the carrying frame connected to the heddle frames, reed and rolls.

As illustrated in the drawings, I provide a loom structure having a suitable base designated as an entirety by the numeral 5, and having the upstanding capes disposed at the four corners thereof. A breast beam and a back beam 8 re-

2

spectively interconnect the two front capes 6 and the two rear capes 6. A pair of opposed stationary frame guides 9 are respectively fixed to the ends of the base structure 5, and each has a plurality of frame guiding channels 9a formed therein. Each pair of opposed channels has a heddle frame 10 slidably received therein. Each heddle frame has a plurality of horizontally spaced heddles 10a having the heddle eyes 10b centrally formed therein. The heddles 10a are stretched between longitudinal frame rods 10c and the heddle eyes 10b serve to position one group of threads from the warp in the conventional manner. A plurality of heddleframe lever cradles 11 are normally in lowered position supported by the cushioned stop 12, as best shown in Fig. 1. Each lever cradle 11 has a frame-receiving groove formed therein to receive the lower rail of the heddle frames 10 which are supported on the cushioned rests 12a. These cradles are adapted to be individually raised as by the levers 13, which are pivotally connected thereto, and swing on the pivot fixed in the base structure 5. A push button or handle 13a is fixed to the outwardly extending end portion of each lever 13, and a spring tensioned latch plate 14 is swingably mounted on the end portion of the base structure 5, and has a slot 14a formed therethrough for each of the levers 13. Each slot 14a has a stop projection 15 formed therein to receive the respective depressed lever 13 and hold the same in depressed position. When the outwardly extending end portion of one of the levers 13 is depressed, the respective cradle 11 fixed thereto is elevated and the heddle frame 10 received in the cradle groove is pushed up to raise the threads extending through the heddle eyes 10b to permit the weaving operation to be carried on in the conventional manner. It should be noted that whenever one of the levers 13 is depressed downwardly the camming surface immediately above the respective stop projection 15 is engaged to shift the entire plate 14 against the force of the spring 14b, and any of the other levers which are down during this shifting movement will be released to drop the particular heddle frame raised thereby.

A pair of rotatable rolls 16 and 17 are respectively mounted at the front and back of the loom structure, as by being respectively re-

ceived in the slots 6a formed in the front and back pairs of capes 6. Suitable keeper plates 6b are pivotally mounted on the respective capes 6 and normally retain the trunnions of the rolls within the respective slots 6a. A pawl and ratchet mechanism positively holds each of the rolls against rotation. A pawl 17a is mounted on at least one front and one back cape 6, and toothed ratchets are respectively mounted on the rolls 16 and 17 to maintain tension on the cloth and warp respectively wound thereon.

A batten 18 is swingably mounted on a suitable rod 19 and a reed 20 is removably anchored in the upper portion of said batten, as best shown in Fig. 2. The upper batten bar 18a is vertically adjustable on said batten as by the elongated slots 18b, and the bolts and wing nuts 18c securely clamp said batten bar against the reed 20. The elongated slot 18b permits reeds of various width to be used, and these slots extend upwardly through the upper ends of the batten uprights to permit the top bar 18a to be entirely removed and permit the warp extending through the reed 20 to be removed bodily from the mounting structure along with the reed and heddle frames.

A removal and carrying frame, designated as an entirety by the numeral 21, is provided and has an overhead support frame with a carrying handle 22 fixed at its ends to cross bars 23. A pair of heddle frame receiving cross slats 24 are swingably mounted on blocks 25 fixed to the underside of the respective cross bars 23. One of the slats 24 in Fig. 1 is shown in closed position, while the other slat is shown in open position. A pair of slat retaining latch members 26 are mounted in transversely spaced relation to the blocks 25 and respectively receive the end portions of the slats 24, as illustrated. A pair of reed hooks 27 are slidably mounted on rod 28 which extends between cross bars 23, and two pair of roll clips 28 are connected to the respective ends of said cross bars 23, as by the flexible elements 29.

The following is a description of the operation of my improved loom structure. The rolls 16 and 17 are mounted in their respective slots 6a, and the heddle frames 10 are mounted in the respective frame guiding channels 9a of the guides 9 and are received in the grooves in cradles 11. The reed 20 is inserted in the batten 18 clamped between said top bar 18a and the lower grooved bar disposed forwardly and below said top bar 18a, as best shown in Fig. 2. The loom is prepared for weaving in exactly the same way as conventional looms and is operated during the weaving operation in the same manner as conventional looms. The heddle frames are selectively vertically reciprocated by the levers 13. The warp, of course, extends upwardly from the warp roll 17 at the rear of the loom and over the back beam 8, through the respective eyes 10b of the heddle frames 10, through the reed 20, and the cloth extends over the breast beam 7 to the cloth or front roll 16 on which the woven cloth is wound.

In order to remove the frames, the reed and the two rolls 16 and 17, along with the work, the top batten bar 18a is removed from the batten to release the reed 20 and the two beams 7 and 8 may be removed from the respective capes 6, which is permitted by the removable dovetail joints therebetween. The rolls 16 and 17 can now be released from their respective slots and clipped to the roll clips 28, the reed being 75

received in the hooks 27 and the upper rails of the frame being supported on the cross slats 24, which are, of course, swung into closed position to retain the same thereon. This permits the entire work, the heddle frames, the reed, and the rolls to be bodily removed by lifting the removal and carrying frame 21.

It will be seen that I have provided a relatively simple, yet highly efficient and ingenious mechanism for permitting work to be bodily removed from a loom for inserting a separate piece of work without requiring the work to be replaced to be removed from the reed, heddle frames and rolls, thus permitting easy connection and exchange of work pieces, while using the same main loom structure. This is particularly valuable where weaving is being taught and permits each student to set up his or her own loom extremely quickly and easily without requiring a separate base structure for each student.

It will, of course, be understood that various changes may be made in the form, details, arrangement and proportions of the various parts without departure from the scope of the present invention, which, generally stated, consists in the matter shown, and described, and set forth in the appended claims.

What I claim is:

1. A weaving loom comprising a base, a pair of upstanding opposed frame guides fixed to the ends of said base and having frame guiding means formed therein to slidably receive a plurality of heddle frames, a plurality of frame receiving cradles mounted between the bottoms of said guides, means for individually raising said cradles, a batten swingably mounted on said base and having a removable top bar, a breast beam and a back beam respectively mounted along the sides of said base structure, and means connected with said base structure for removably journaling a pair of rotatable rolls.

2. A weaving loom comprising a base structure, a pair of opposed upright guides each having a plurality of respectively opposed guiding means formed therein, a plurality of heddle frames respectively mounted in said opposed guiding means, a frame receiving cradle mounted under each frame, means for individually raising said cradles to selectively push said frames upwardly, a batten swingably mounted on said base structure, a reed removably mounted on said batten, a breast beam connected across the front of said base, a back beam connected across the back of said base, a front roll rotatably journaled below said breast beam, and a back roll rotatably journaled below said back beam, said rolls, frames, and reed all being removable as a unit from said base and mounting structure to permit a piece of work to be removed without removing the warp from the frames, reed and rolls.

3. A weaving loom comprising a base, a pair of opposed upright guides fixed at the ends of said base and each having a plurality of respectively opposed guiding means formed therein, a plurality of heddle frame pusher cradles mounted between the bottom portions of said two guides, an operating lever connected to each of the cradles and extending outwardly therefrom beyond the periphery of the base, a spring latch mechanism for selectively holding one of said levers in cradle raising position and for releasing said lever when another lever is shifted to cradle raising position.

4. A weaving loom comprising a base struc-

ture, a pair of opposed upright guides each having a plurality of open topped, respectively opposed guiding channels formed therein, a plurality of heddle frames removably mounted in the respectively opposed guiding channels, a heddle frame lifting mechanism from which the heddle frames may be easily removed, a batten swingably mounted on said base structure and having a removable top batten bar to permit a reed to be lifted therefrom, two pair of upright capes, a breast beam mounted across the front pair of capes and a back beam mounted across the two rear capes, a pair of rotatable rolls respectively journaled in the front and rear pair of capes, and means permitting said rolls to be removed from said capes.

5. The structure set forth in claim 4 and said

two beams being removable to facilitate removal of the rolls from the capes.

HILMA L. G. BERGLUND.
